UNITED STATES PATENT OFFICE.

WILLIAM CROSS, OF WINNIPEG, CANADA.

CAR-AXLE BOX.

SPECIFICATION forming part of Letters Patent No. 448,130, dated March 10, 1891.

Application filed July 2, 1890. Serial No. 357,578. (No model.)

To all whom it may concern:

Be it known that I, WILLIAM CROSS, residing at Winnipeg, Manitoba, Canada, have invented a new and Improved Car-Axle Box, 5 of which the following is a specification.

The invention is an improvement in the class of car-axle boxes in which the axle-journals rotate in contact with a liquid lubricant held in the bottom of the boxes.

10 The invention consists in the construction, arrangement, and combination of parts, as hereinafter described.

Figure 1 is a vertical longitudinal section of the axle-box. Fig. 2 is a horizontal section, the upper half of the view being taken on the plane of the top of the brass and the lower half having the brass removed; and Fig. 3 is a vertical transverse section in two different planes, the left-hand portion being 20 taken on line *x x* and the right-hand portion being taken on line *y y*.

In the drawings the axle is reduced in diameter just outside the car-wheel for the space of about two and a half inches, and is 25 then increased in diameter about one inch or a half an inch all around to form the journal A.

C is the axle-box, which upon the inner side is provided with a dirt-guard D, in the form 30 of a packing held in the axle-box and embracing the narrow neck portion of the axle.

B is a brass block, which is inserted between the top of the axle-box and the upper side of the journal. When this brass is inserted, it 35 raises the axle-box, so that the dirt-guard and casing come up close to the smaller part of the axle. This causes as much of the journal as is larger than the axle at the dirt-guard to drop below the level of the opening in the 40 casing, and as the bottom of the casing or box forms a tight oil-reservoir up to the level of the opening through which the neck of the axle passes it will be seen that the greater diameter of the journal A causes its periphery 45 to dip down into permanent or continuous contact with the oil in the subjacent reservoir, thus receiving constant lubrication without waste and without fibrous packing.

E is a tallow-box formed upon the top of 50 the casing and having an outlet at the bot-

tom arranged to discharge into the oil-reservoir below. The object of this is as follows: If the oil in the reservoir below becomes used up to the extent of failing to properly lubricate the journal and heating ensues, this 55 heating will melt the tallow or normally solid lubricant in this box E, which will flow down into the oil-reservoir below and raise the level of the normally liquid oil to a renewal of perfect contact with and lubrication of the journal. 60

In constructing the brass B it is formed with a right-angular arm or extension B², which descends to the center of the journal and abuts against the end thereof. This center bearing or stop is held up against the end of the journal by a cross-bar F, whose ends are driven into seats f, formed in the sides of the journal-box. This not only secures the brass in place, but it prevents the longitudinal 70 vibration of the journal in the box.

The pendent portion or arm B² of the brass B is tapered or cut away on its sides, as shown by dotted line in Fig. 3, thus leaving a space between its sides and the adjacent sides of 75 the axle-box for passage of a lubricant escaping from the outlet of tallow-box E. Thus the melted tallow flowing down over the face of the arm of brass B upon the cross-bar F diverges, in part, laterally and enters the 80 axle-box through the lateral passages formed as above described, while a portion flows over the front of the cross-bar, and thus reaches the same place.

Having thus described my invention, what 85 I claim, and desire to secure by Letters Patent, is—

The combination, with the axle-journal, the axle-box, and its front cross-bar, of the bearing-block B, having its pendent front end tapered, thus forming side passages for the lubricant, as specified, and the tallow-box E, having a bottom outlet located in front of said block and directly over the cross-bar, as and for the purpose specified. 90

WILLIAM CROSS.
